SUCTION CLEANING TOOL

Edward R. Swann, North Canton, Ohio, assignor to The Hoover Company, North Canton, Ohio, a corporation of Ohio

Application August 14, 1958, Serial No. 52,205

Term of patent 14 years

(Cl. D9—2)

Fig. 1

Fig. 2

Fig. 3

The dominant features of the design reside in the portions of the drawing shown in solid lines.

I claim:

The ornamental design for a suction cleaning tool, substantially as shown and described.
